UNITED STATES PATENT OFFICE

FRANZ KRUCKENBERG, OF HEIDELBERG, GERMANY

DEVICE FOR HEATING AND VENTILATING SUSPENDED HIGH-SPEED RAILWAY CARS

Application filed November 12, 1927, Serial No. 232,929, and in Germany November 16, 1926.

This invention relates to suspended high-speed cars of the kind in which the passenger seats are arranged along the side walls of the car in such a manner that the passengers sit 5 with their backs to these walls, whereas between the two rows of seats a gangway is left in which passengers can stand. The present invention relates to means for heating and ventilating cars of this type, but in 10 contradistinction to letting the fresh air rise from the bottom to the top only between the rows of seats, I have provided means for introducing fresh air also between the backs of the passengers and the side walls of the car 15 in order to counteract the strong cooling of the air within the car by the side walls; and, besides, means are provided for discharging the bad air from above the heads of the sitting passengers, as well as from above the heads 20 of the standing ones. The means for this latter purpose consist in two vertical longitudinal screens suspended from those portions of the ceiling of the car which are located just over the heads of the passengers so as to separate 25 the spaces above the heads of the sitting persons from the space above the heads of the standing ones. Said screens consist of an opaque material, that is to say, they are impermeable to light, and the standing persons 30 cannot therefore look through them. There are windows in the side-walls over the heads of the sitting persons and the said screens are located between the windows of the two side walls of the cars. Preventing the standing 35 persons from looking through said windows is a precautionary means, in that the very quickly running cars assume in curves correspondingly oblique positions, in consequence whereof the outer objects seem to be more or 40 less oblique which will give rise to uneasiness, anxiety and nausea if the standing persons can look out of the car. This is by far less the case with the sitting persons because they look in the direction to the sky through the 45 windows over the oppositely seated passengers. Moreover, the sitting persons can look only through a comparatively small portion of the opposite windows because the screens are in the direction of sight.

50 The invention is illustrated diagrammati-

cally and by way of example on the accompanying drawing on which is shown a vertical transverse section through a suspended high-speed railway car designed according to the invention. On the righthand side of the car 55 is shown a standing person intending to sit down but having not yet begun to do so, and the same person is shown sitting on the bench or the like, and there are intermediate representations showing again the same person in 60 various positions as occurring when sitting down. 2 denotes the vertical longitudinal screens mentioned in the preceding part of this specification, and 1 are the usual holding rods which are arranged as low as possible, 65 preferably below the lower edges of the screens, as shown in the lefthand part of the figure. The rod 1 is located between the horizontal top planes of a sitting person of normal size and of a standing person of normal 70 size, and its position with respect to the sitting persons is such that one does not contact with it when sitting down and when rising.

The screens 2 may be rendered non-transparent by advertisements, also by diapositives or the like used at the same time for decorating purposes. It might seem possible to omit the screens and make use of opaque windows, but I know from experience that 75 this will make the passengers uneasy and oppress them.

The wall of the car is, of course, during the cold season considerably cooled by the outer air especially during running; this is even more true of the windows 3 from which currents of cold air flow down onto the necks and the napes of the passengers, as indicated on the righthand side of the figure. In order to do away with this disagreeable and hurtful drawback, a screen 4 (lefthand side of the figure) is provided on the top of the back of the bench or the like, this screen, which is a protective screen, extending upwardly to the proximity of the windows 3 so that the air cooled by the same is kept off the necks and the napes of the passengers. In fact, however, the cold air does not pass away down through the space between the screen 85 and the back of the bench on the one side and 90

the inner wall of the car on the other side down to the bottom of the car, but provision is made that a current of heated air passes upwards through the space between said inner wall and the opposite parts, as more fully dealt with hereinafter. The upper edge of the protective screen 4 may bear tubular lamps 11.

Below the floor of the passenger room is a space *a*, and above the ceiling of said room a space *b*, and provision is made that the pressure in the space *a* is always greater than that in the space *b*, so that there arise air currents, as indicated by the arrows. The outer air enters into the space *a* through bottom apertures 5 which are provided with regulating means, and the bad air leaves the car through apertures 7 located in the top of the car shell at the spaces *b*. The air flowing from the space *a* into the interior of the car is divided by vertical sheet-metal walls 8 (lefthand side of the figure) into two currents, the one flowing into the passenger room, the other flowing along the inner sides of the car shell upwardly to the windows 1 and further upwards through apertures 10 into the space *b*. The air present in the passenger room escapes through apertures 9 also into the space *b*, which communicates with the outer air through the apertures 7. The bent-off lower portion of the sheet-metal walls 8 may be hinged to the upper part, that is to say, it may be movable and adjustable, and means may be provided for affixing it in its adjusted position. 6 denotes heating bodies arranged in the space *a*.

I claim:

1. A device for heating and ventilating suspended high-speed railway cars, comprising, in combination with the car shell and with a chamber provided between the lower portion of the shell and the floor of the passenger space, heating bodies in said space, and air-supply apertures in said shell portion: means for distributing the heated fresh air below the seats into the passenger room and into a passage provided between the backs of the seats and the lateral shell portions, a ceiling separating the passenger room from a chamber above it, vertical screens extending along at said ceiling over the passenger seats and separating the space above the heads of the sitting passengers from the space above the heads of the passengers standing between the sitting ones, and air-discharge apertures from both these spaces into the top chamber and from this into the atmosphere.

2. A device for heating and ventilating suspended high-speed railway cars, comprising, in combination with the car shell and with a chamber provided between the lower portion of the shell and the floor of the passenger space, heating bodies in said space, and air-supply apertures in said shell por-

tion: means for distributing the heated fresh air below the seats into the passenger room and into a passage provided between the backs of the seats and the lateral shell portions, upwardly directed screens secured to the top-edges of the seatbacks, and air discharge apertures in the top of the car.

3. A device for heating and ventilating suspended high-speed railway cars, comprising, in combination with the car shell and with a chamber provided between the lower portion of the shell and the floor of the passenger space, heating bodies in said space, and air-supply apertures in said shell portion: means for distributing the heated fresh air below the seats into the passenger room and onto a passage provided between the backs of the seats and the lateral shell portions, upwardly directed screens secured to the top-edges of the seat-backs, a ceiling separating the passenger room from a chamber above it, and air-discharge apertures in said ceiling and in the top of the car shell.

4. A device for heating and ventilating suspended high-speed railway cars, comprising, in combination with the car shell and with a chamber provided between the lower portion of the shell and the floor of the passenger space, heating bodies in said space, and air-supply apertures in said shell portion: means for distributing the heated fresh air below the seats into the passenger room and into a passage provided between the backs of the seats and the lateral shell portions, upwardly directed screens secured to the top-edges of the seatbacks, a ceiling separating the passenger room from a chamber above it, vertical screens extending along at said ceiling over the passenger seats and separating the space above the heads of the sitting passengers from the space above the heads of the passengers standing between the sitting ones, and air-discharge apertures from both these spaces into the top chamber and from this into the atmosphere.

5. In a ventilating apparatus for railway cars or the like, the combination of a car having a seating space for seated passengers, and an adjacent standing space for standing passengers, of separate means for venting the foul air from the seating space and from the standing space, and a vertical partition extending downwardly between the standing space and the seating space.

6. The structure as set forth in claim 5 wherein separate entrances are provided for admitting fresh air to the standing space and the seating space.

In testimony whereof I have affixed my signature.

FRANZ KRUCKENBERG.
